UNITED STATES PATENT OFFICE.

RALPH L. LOOBY, OF NEW YORK, N. Y.

CARBURETER.

No. 916,465.

Specification of Letters Patent. Patented March 30, 1909.

Application filed September 9, 1908. Serial No. 452,173.

To all whom it may concern:

Be it known that I, RALPH L. LOOBY, a citizen of the United States, residing in the borough of Manhattan, city, county, and State of New York, have invented certain new and useful Improvements in Carbureters, of which the following is a specification.

This invention is directed to the provision of an improved form of carbureter adapted particularly for use in connection with a gasolene engine on an automobile.

The object of the invention is to effect certain improvements in the construction of carbureters. For this use, the improvements involving the provision of a carbureter which is simple in construction and can be manufactured at low cost and with which a good quality of gas, free from bubbles or minute drops of gasolene, is obtained.

I have illustrated the preferred embodiment of my invention in the accompanying drawings in which—

Figure 1 is a central section of the carbureter, Fig. 2 is a top view of the same, Fig. 3 is a section on line 3--3 of Fig. 1, Fig. 4 is a view in elevation of a portion of the carbureter and Fig. 5 is a sectional detail view on the line 5--5 of Fig. 1.

Referring to these drawings, the carbureter consists of two circular receptacles one within the other, a spiral passageway within the space between these two receptacles, an opening from one receptacle to the other at the bottom thereof and valve mechanism at the top of the two receptacles. The larger or outer receptacle is preferably a circular sheet-metal can 1, secured to and depending from a frame-plate 2; the smaller receptacle 40 is a metallic tube 3 and is secured at its upper end to the plate 2 and at its lower end to the bottom of the can 1, this tube being concentric with can 1. In the space between the can 1 and tube 3 is a spiral passageway 45 of small pitch formed by a ribbon of sheet-metal 4, wound spirally on edge upon the tube 3. Near its upper edge the can 1 has an opening in the wall thereof to admit air to the top of the spirally arranged passageway 50 and at the bottom of the tube 3 an opening is provided in the wall of the tube to connect the bottom of the spiral passageway with the interior of tube 3. The gasolene is admitted to the spiral passageway at the top thereof 55 from a pipe 5 by means of a needle valve 6, this valve being movable vertically in a bush-

ing 7 secured on the plate 2. The plate 2 is formed to provide a chamber 8 with which connects a pipe 9, for carrying the gas to the engine or other device in which it is to be used. In the plate 2 and in a cross-piece 10 secured thereto are formed bearings for a shaft 11, which carries a valve 12 and on the upper end of shaft 11, above plate 2, is a handle 13, so that by turning this handle the valve 12 is moved to cover more or less of the opening through pipe 9.

Secured to or formed integral with the handle 13 are two arms 14 and 15 carrying an arc-shaped piece 16. This piece has a slot therein through which the upper end of the valve 6 extends and this valve is provided with nuts or collars 17, one on either side of the piece 16. The means for securing one end of the piece 16 to the end of the arm 15 includes a screw 18 entering a threaded opening in the end of arm 15, this screw being preferably provided with a knurled head. The screw 18 passes through an opening in piece 16 and is provided with nuts or collars, one on either side of the piece 16 so that turning the screw in its opening in arm 15 will raise or lower the end of the piece 16. The means for securing the other end of the piece 16 to the end of arm 14 is such as to permit the piece 16 to be moved thus by screw 18. The surfaces of the nuts or collars which coat with the opposite sides of piece 16 are preferably spherically formed so as to more readily permit of the angular adjustment of piece 16.

In using the carbureter, the liquid gasolene is allowed to drop from the valve 6 down upon the bottom 4 of the spiral passageway between the can 1 and tube 3, and the gasolene runs down the inclined surface more or less. Air is drawn by the engine or other device through the opening in can 1, and downwardly through the spiral passageway between can 1 and tube 3, and in passing over the thin film of gasolene which overlies the bottom of the spiral passageway, this air picks up gasolene vapor so as to form a volatile gas. At the bottom of the spiral passageway the gas passes into the opening in tube 3 and then passes upwardly through tube 3 into chamber 8 and then through pipe 9 to the engine. The amount of vapor entering tube 9 is controlled by the valve 12, the position of which may be adjusted by turning the handle 13. Adjustment of this throttle-valve 12 by means of

handle 13, also adjusts the position of the needle valve 6 so as to vary the amount of gasolene entering the carburetor simultaneously with the adjustment of the supply of vapor passing through pipe 9. It will be seen that as handle 13 and valve 12 are turned, the arc-shaped piece 16 is turned relatively to the needle valve 6 and as this piece lies at an incline, its movement causes a raising or lowering of the valve 6. If it is found that the rate of inflow of gasolene is greater or less than that desired, the valve mechanism may be so adjusted as to permit a faster or slower feed of the gasolene. This adjustment is effected by turning the screw 18 so as to increase or diminish the inclination of piece 16, and it will be seen that when this inclination is changed, the amount of vertical movement of valve 6 when valve 12 is closed and opened, will be correspondingly changed.

The carburetor above described is very simple in construction, may be manufactured at low cost and will withstand the hard usage to which it is necessarily subjected, when used on an automobile. Furthermore, with this form of carburetor, a gas of very good quality is obtained, since the construction is such that bubbles or fine drops of liquid gasolene will not be carried into the cylinder of the engine. This is due to the fact that the gasolene is spread out over a large surface on the bottom of the spiral passageway so that the air passing through the carburetor moves over a large area on which there is a film of gasolene and then rises upward vertically before coming to the valve mechanism and the pipe leading to the engine.

Having described my invention what I claim as new therein and desire to secure by Letters Patent of the United States is:

1. A carburetor consisting of a receptacle, a tubular member mounted therein, a spiral passageway in the space between the receptacle and member, said tubular member having an opening therein at the bottom thereof connecting said passageway and the interior of the member, and means for admitting air and liquid hydrocarbon to said receptacle at the upper end of said passageway, the upper portion of said tubular member forming the mixture outlet, substantially as set forth.

2. A carburetor consisting of a receptacle, a tubular member mounted therein, a spiral passageway in the space between the receptacle and member, said tubular member having an opening therein at the bottom thereof connecting said passageway and the interior of the member, means for admitting air to said passageway at the upper end thereof, a

valve for admitting a liquid hydrocarbon to said passageway at the upper end thereof, and a valve at the upper end of said tubular member for controlling the delivery of gas from the carburetor, substantially as set forth.

3. A carburetor consisting of a receptacle, a tubular member mounted therein, a spiral passageway in the space between the receptacle and member, said tubular member having an opening therein at the bottom thereof connecting said passageway and the interior of the member, means for admitting air to said passageway at the upper end thereof, a valve for admitting a liquid hydrocarbon to said passageway at the upper end thereof, a valve at the upper end of said tubular member controlling the delivery of gas from the carburetor, and means for simultaneously operating said valves, substantially as set forth.

4. A carburetor consisting of a receptacle, a tubular member mounted therein, a spiral passageway in the space between the receptacle and member, said tubular member having an opening therein at the bottom thereof connecting said passageway and the interior of the member, means for admitting air to said passageway at the upper end thereof, a valve for admitting a liquid hydrocarbon to said passageway at the upper end thereof, a valve at the upper end of said tubular member controlling the delivery of gas from the carburetor, means for simultaneously operating said valves, and means for adjusting the operating means for one of said valves, substantially as set forth.

5. A carburetor consisting of a receptacle, a tubular member mounted therein, a spiral passageway in the space between the receptacle and member, said passageway being connected with the interior of said member, means for admitting air to said passageway at a point distant from said connection, a valve for admitting a liquid hydrocarbon to said passageway, a valve-member pivotally mounted within said tubular member near one end thereof and controlling the delivery of gas therfrom, an inclined member moving with said valve-member and coacting with said valve for the hydrocarbon to operate the latter, and means for adjusting the inclination of said inclined member, substantially as set forth.

This specification signed and witnessed this 5th day of September, 1908.

RALPH L. LOOBY.
